UNITED STATES PATENT OFFICE.

EDWARD J. LOBDELL, OF MARIETTA, OHIO.

DESIGN FOR A WHEEL-RIM.

SPECIFICATION forming part of Design No. 25,425, dated April 21, 1896.

Application filed December 19, 1895. Serial No. 572,719. Term of patent 7 years.

To all whom it may concern:

Be it known that I, EDWARD J. LOBDELL, of Marietta, in the county of Washington and State of Ohio, have invented a certain new and useful decorative Design for Wheel-Rims; and I do hereby declare the following to be a full, clear, and exact description of the invention, such as will enable others skilled in the art to which it pertains to make and use it, reference being had to the accompanying drawings, which form part of this specification.

This invention pertains to a decorative design for wheel-rims, which is illustrated by the accompanying drawings, wherein—

Figure 1 is a side elevation of the rim. Fig. 2 is a plan view of the inner surface of a portion thereof.

The design consists of a wheel-rim having on its inner surface, and at each side of the transverse center or spoke line, a continuous vine. Thus two distinct circles of vine ornamentation, one on each side of the spoke-line, are provided for the inner or concave side of the rim. 25

I claim—

The design for a wheel-rim, substantially as herein shown and described.

In testimony whereof I affix my signature in presence of two witnesses.

EDWARD J. LOBDELL.

Witnesses:
